UNITED STATES PATENT OFFICE

1,968,137

BATTERY TERMINAL CLAMP

Allie D. Gay, Port Arthur, Tex.

Application July 12, 1933, Serial No. 630,123

1 Claim. (Cl. 173—259)

The present invention relates to a battery terminal clamp and has for its prime object to provide a device of this nature which is exceedingly simple in its construction, easy to manipulate, 5 thoroughly efficient and reliable in use and operation, and otherwise well adapted to the purpose for which it is designed.

With the above and numerous other objects in view as will appear as the description proceeds, 10 the invention consists in certain novel features of construction, and in the combination and arrangement of parts as will be hereinafter more fully described and claimed.

In the drawings:

- 15 Figure 1 is a top plan view of a battery showing the clamps engaged in place on the post.
 Figure 2 is a detail top plan view of one of the clamps showing one end in section.
 Figure 3 is a side elevation thereof.

- 20 Figure 4 is another side elevation thereof taken opposite to that shown in Figure 3.
 Figure 5 is a sectional plan view of the clamp showing the same partially opened.

- Figure 6 is a detail view showing the inner side 25 of the ear of the detachable section, and

Figure 7 is a detail view of the bolt and nut.

Referring to the drawings in detail it will be seen that numeral 5 denotes an elongated body formed on the inner side adjacent one end with 30 a semi-cylindrical pocket or recess 6 and from said end extends an ear 7 which is provided with a threaded aperture. The other end of the body 5 extends laterally and terminates in an overlapping hook like extension 8. From said other end 35 extends outwardly a threaded stud 9 so that a suitable coupling 10 may be used for engaging a cable with the clamp. Numeral 11 denotes a detachable section having on its inner side a semi-cylindrical recess or pocket 12 to be disposed opposite the pocket 6 so that battery post 14 may 40 be received therein. From the end adjacent the recess 12 the detachable section 11 is provided with an ear 15 having an opening 16 therethrough larger in diameter than the threaded opening of 45 the ear 7 and having the inner portion thereof countersunk as at 17. This opening is oblong rather than round as clearly illustrated in Figure 6. Numeral 18 denotes a bolt having the usual head 19 and the usual threaded portion 20. A 50 nut 21 is threaded on the bolt, up to the unthreaded portion thereof and that face of the nut which is opposite the head 19 is convexed as indicated at 22 as is also the opposed face 23 of the head 19. The other end of the section 55 11 has a rounded or curved face 25 for cooper-

ating with the inner curvature of the hook extension 8. By manipulating the bolt 18 it will readily be seen that the clamp may be opened or closed with respect to the battery post.

It is thought that the construction, operation, 60 utility and advantages of this invention will now be clearly understood by those skilled in this art without a more detailed description thereof.

The present embodiment of the invention has been described in considerable detail merely for 65 the purposes of exemplification since in actual practice it attains the features of advantage enumerated as desirable in the statement of the invention and the above description.

It will be apparent that changes in the details 70 of construction, and in the combination and arrangement of parts may be resorted to without departing from the spirit or scope of the invention as hereinafter claimed or sacrificing any of its advantages.

Having thus described my invention, what I claim as new is:—

A battery post clamp comprising a pair of elongated members having straight inner faces and each member having a recess in an intermediate part of its inner face, said recesses being adapted to receive a battery post, a hook formed on one member at one end thereof, the hook extending outwardly from the straight or flat face of the member, with the inner wall of the hook curving outwardly and toward the recess from said flat face, with the end of the hook rounded, the corresponding end of the other member curving outwardly and toward the recess therein from the flat or straight face of said other member and the outer face of said other member having a recess therein adjacent its curved end for receiving the rounded end of the hook when the two members are swung away from each other, 80 the curved end of said other member engaging the curved wall of the hook, the hook and said curved end being spaced a considerable distance from the recess parts to permit swinging movement of said other member toward and away 85 from the post, and a bolt passing through the members adjacent the other ends thereof, said bolt passing through a plain elongated hole in one member and a threaded hole in the other, 90 said bolt having a collar thereon for engaging a part of the inner face of the member having the plain hole therein, the inner end of the elongated hole being formed with a rounded countersink and the collar having a rounded face fitting in the countersink.

ALLIE D. GAY. 110
